FLEXIBLE BINDER POST

Alfred Mullikin, San Francisco, Calif.

Application November 23, 1946, Serial No. 711,963

2 Claims. (Cl. 85—1)

1

This invention relates to loose leaf binders and more particularly to flexible binding posts therefor.

Among the objects of the invention is the provision of a resilient binding post for loose leaf binders that will permit the binder to open flat in use.

Another object is the provision of means for preventing the elongation of the binding posts beyond the predetermined capacity of the binder.

Another object is the prevention of lateral distortion of the spiral binding post in operation.

A further object is to avoid the necessity for providing hinge portions in the cover boards adjacent the binding posts.

Other objects and advantages will appear as the description progresses. In the specification and the accompanying drawings the invention is disclosed in its preferred form. But it is to be understood that it is not limited to this form because it may be embodied in modifications within the spirit of the invention as defined in the claims following the description.

In the one sheet of drawings:

Fig. 1 is a vertical section of a binder having this invention applied thereto and shown in full lines.

Fig. 2 is a vertical section of a binding post constructed in accordance with this invention.

In detail the structure shown in Fig. 2 comprises the resilient coil spring post 1, preferably composed of hard metal wire spirally wound in close formation, without space between the coils, and cut to the desired overall length.

The binding screws 2, 3 have external threads matching the pitch of the helix of the coil post, but slightly larger in outside diameter so that the threads of the screw will wedge snugly into the respective ends of the post 1, and prevent their dislodgment therefrom, except by manual withdrawal. These screws have overhanging curved heads 4, 5, with transverse screwdriver slots 6, 7 respectively.

These screws also have internally threaded axial holes therethrough, to receive the threaded ends 8, 9 of the flexible tie-wire 10. It is preferable to form these threaded ends on the wire by the thread rolling method, which forms an enlarged diameter of the threaded portion without reducing the gauge of the wire 10, and without causing surface scores therein liable to cause breakage when flexed. The internal threads are the same pitch as the external threads, to prevent binding action.

In assembling the binder, as in Fig. 1, the

2

wire end 9 is inserted into the end of the screw 3 for about one-half its length. The screw 3 is then inserted into the end of the coil 1 and turned by a screwdriver in the slot 7, until the end of the coil abuts the underside of the head 5 and jams.

The ferrule 11 having the flange 12 is then dropped over the coil 1 and against the head 5. The cover-board 13 has a hole therethrough fitting the ferrule 11. The loose leaves 14 similarly punctured are stacked on the cover 13 to the height of the binding post. The top cover board 15 having a hole therethrough is laid on top of the sheets surrounding the coil post 1.

The ferrule 16 is then pushed through the hole in the top cover-board and telescopes over the top end of the coil, with its flange 17 lying on top of the top cover-board.

The screw 2, having a countersunk center hole internally threaded, is entered into the upper end of the coil 1 and turned by a screwdriver in the slot until the center hole engages the threaded end 8 of the flexible tie-wire 10. The screw 2 is then turned until its underside binds against the flange 17 and compresses the leaves 14 surrounding the post between the top and bottom cover-boards 13, 15. The tie wire 10 prevents any elongation of the post 1 during and after assembly and in use. For freedom of operation the mass of leaves should not be compressed too compactly.

The invention is intended more particularly as a permanent binder, for that reason the posts are made of a predetermined length depending upon the thickness of the book desired. These posts are inserted at intervals across the width of the cover and the thickness of the mass of leaves to give stability to the assembly. In general practice the wire used will range from 17 to 20 B & S gauge, more or less, according to the size and the mass of leaves to be bound.

If the covers such as 13, 15 are of wood or other hard material the ferrules 11, 16 may be omitted and the ends of the spring entered therein with the heads 4, 5 bearing against the covers, with or without an interposed washer. The external threads at 2, 3, may also be omitted in lighter structures.

The invention operates substantially as follows: When fully assembled as in Fig. 1, the book is opened in the usual manner. This causes the post 1 and the tie-wire 10 to bend backward in a true arc until the outside covers 13, 15 will lie in a flat plane. The stack of leaves X will move forward in an arc common with the arc of the post

coils 10, the series of loops forming the helix of the coil will move slightly relative to each other without opening any space between them on the longer arc at the front of the coil, because of the non-extension of the flexible tie wire 10 which bends in an arc substantially concentric with the arc formed at the rear side of the coil.

The closed structure of the coil walls extending slightly oblique or helically to the plane of the sheets 14 also prevents them from entering the walls of the coil 1, in the open position of the book, since the leaves are perpendicular at all times to the axis of the coil. This is further assured by the burr that usually surrounds punched holes in paper sheets.

This invention is not to be confused with extensible coil posts used in extensible binders in which the post elongates to accommodate added sheets, beyond the original length of the post.

Having fully described this invention and its mode of operation what I claim and desire to secure by Letters Patent is:

1. A flexible post in the class described, comprising a close wound helical spring; binding screws in the opposite ends of said spring and having external threads engaging the helix pitch of said spring and having internal threads of substantially the same pitch; and a single relatively stiff but laterally flexible tie wire coaxial with said spring and having externally threaded ends engaging said internal threads of said spring and having externally threaded ends engaging said internal threads in said binding screws respectively.

4
ends engaging said internal threads in said binding screws respectively.

2. A flexible post in the class described, comprising a close wound helical spring; binding screws in the opposite ends of said spring and having external threads engaging the helix pitch of said spring and having internal threads of substantially the same pitch and heads overhanging the diameter of said spring, respectively; and a single relatively stiff but laterally flexible tie wire coaxial with said spring and having externally threaded ends engaging said internal threads in said binding screws respectively; and ferrules surrounding the respective ends of said spring with annular flanges bearing beneath said overhanging heads of the said screws respectively.

ALFRED MULLIKIN.
